COMBINED FRUIT PRESS AND NUT CRACKER
OR THE LIKE

Carmelo Basilotta, 35—42 80th St.,
Jackson Heights, N.Y.

Filed Apr. 1, 1965, Ser. No. 84,559

Term of patent 14 years

(Cl. D89—1)

Fig. 1.

Fig. 2.

Fig. 3.

Fig. 4.

Fig. 5.

FIGURE 1 is a top plan view of a combined fruit press and nut cracker or the like showing my new design;

I claim:

The ornamental design for a combined fruit press and nut cracker or the like as shown.
